UNITED STATES PATENT OFFICE

1,929,361

SUCTION FOOT FOR PAPER SEPARATING DEVICES

Eric Harry Liljebladh, Gottenborg, Sweden,
assignor to Aktiebolaget Westerlin & Co., Got-
tenborg, Sweden

Application January 21, 1932, Serial No. 587,992,
and in Sweden October 26, 1929

4 Claims. (Cl. 271—27)

The present invention relates to suction feet for pneumatic paper-separating devices, by means of which the sheets from a pile of paper are separated one by one from the pile in order to 5 be fed to a printing press or similar machine.

More specifically the invention relates to suction feet, for the above mentioned purpose, of the kind which are provided with a movable suction member adapted to seize the uppermost sheet 10 of the pile and, due to the vacuum, to be lifted up together with this sheet.

The object of the invention is to provide an improved suction foot of this kind which is simple in construction and reliable in action.

According to the present invention, the movable suction member comprises a frame embracing the suction opening of the suction foot and swingably mounted on the suction foot in such a manner that, when the suction foot approaches 20 the pile, the frame places itself upon the uppermost sheet and, when this adheres, swings upwardly, bending the adhering sheet against the suction foot.

The invention is illustrated in the accompanying drawing in which Figures 1 and 2 show the suction foot from the side with the frame in two different positions; Figure 3 is a section through the suction foot; Figure 4 shows the suction foot from beneath; Figure 5 is an end 30 view of the suction foot, and Figure 6 is a plan view of the same.

The suction foot comprises a head 1 which is fixed by means of a screw 1a to a horizontal bar 2 passing through a bore 2a in the head. By a 35 mechanism of known form (not shown in the drawing) the bar 2 is moved to and from the top of the pile of paper 3, the sheets of which are to be separated. The head 1 is provided with a channel 4, forming a suction opening 4a at the under side of the head and communicating with a laterally projecting pipe socket 5 intended to be connected to a flexible suction tube 5a. The head 1, one side 6 of which has the form of a portion of a surface of a cylinder is embraced by a 40 frame 7, provided with a portion 8 in the form of a portion of a cylinder, two side portions 9, 9 and a bottom portion 10. The side portions 9, 9 are each provided with a hole 11 through which the bar 2 passes, so that the frame 7 can swing 45 between the positions shown in Figures 1 and 2.

In order to limit the raising movement of the frame 7 there is provided a screw 12 passing through a bore 11a in the head, the lower end of said screw 12 serving as an abutment for the bottom portion 10 of the frame 7 (see Figure 3). 55 One of the side portions 9 of the frame 7 is provided with a projection 13 which limits the downward swinging movement of the frame by co-operating with the pipe socket 5. The bottom portion 10 of the frame 7 is provided with 60 a hole 14, and outside this hole 14 is fixed (to the bottom portion) a common suction ring 15 of rubber, the suction surface of said ring being a little larger than the surface of the bottom portion 10. 65

The operation of the device described is as follows:—

When the suction foot with the frame 7 in a downwardly swung position is lowered towards the pile 3 to the position shown in Figure 1, the frame 7 due to the vacuum in the channel 4 of the head will be swung up to the position shown in Figures 2 and 3 together with the uppermost sheet adhering to the suction ring 15. At this movement the adhering sheet will be bent around the portion 16 of the head, which contributes to separate this sheet from any under sheets, which may be clinging to it. Due to the fact that the suction surface of the suction ring 15 is larger than the surface of the bottom portion 10 of the frame, 75 the sheet seized by the suction ring 15 will under all conditions follow the frame 7 in its upwardly swinging movement. 80

What I claim is:—

1. A suction device for pneumatic separating machines, comprising a suction foot, a frame embracing said suction foot and movable in relation thereto, and means pivotally connecting said frame to the suction foot.

2. A suction device for pneumatic separating machines, comprising a suction foot, a frame embracing said suction foot and movable in relation thereto, means pivotally connecting said frame to the suction foot, and an element in screw threaded engagement with said foot for adjustable positioning thereon in the path of the movable frame to regulate the displacement of the latter.

3. A suction device for pneumatic separating machines, comprising a suction foot having a

lateral projection, a frame embracing said suction foot and movable in relation thereto, means pivotally connecting said frame to the sides of the suction foot, said frame having an extension adjacent its pivotal point and engageable with the lateral projection of the foot to limit the movement of said frame.

4. A suction device for pneumatic separating machines, comprising a suction foot having a lateral projection, a frame embracing said suction foot and movable up and down in relation

thereto, means pivotally connecting said frame to the sides of the suction foot, said frame having an extension adjacent its pivotal point and engageable with the lateral projection of the foot to limit the downward movement of the frame, and an element in screw threaded engagement with said foot for adjustable positioning thereon in the path of the movable frame to regulate the upward displacement of the latter.

ERIC HARRY LILJEBLADH.
